CAVITY RESONATOR CONSTRUCTION

Robert L. Wathen, Hempstead, N. Y., assignor to
The Sperry Corporation, a corporation of Delaware

Application December 11, 1945, Serial No. 634,303

8 Claims. (Cl. 178—44)

1

This invention relates to cavity resonators which are useful at ultra-high-frequencies and, more particularly, to methods of constructing such cavity resonators.

In the construction of cavity resonators it is desirable, especially in electron discharge devices, that the heat that is generated in the resonator be conducted in as efficient a manner as possible to the exterior of the resonator where it may then be dissipated into the surroundings. In order to do this, it is advantageous not only to have the mass of the resonator large, but also that the heat conduction in all directions away from the cavity resonator be large. This prevents local heating from occurring and aids in maintaining all parts of the tube at substantially equal temperatures. Under these circumstances temperature compensation may be carried out intelligently and the problem of frequency stability of an electron discharge or other apparatus incorporating a cavity resonator may be handled with greater ease.

Another desirable feature in the construction of cavity resonators would be the ability to assemble such cavity resonators of different sizes but of the same resonant frequency.

Still another desirable feature in the construction of cavity resonators would be a method whereby the resonators, regardless of the final size and power ratings, could be assembled quickly at any convenient time from a few types of pre-manufactured parts.

In addition to these desirable features, it is necessary that the resonators themselves be so constructed that tuning and removal of electromagnetic energy be easily accomplished.

In cavity resonators, which are to be used in electron discharge tubes or similar devices, it is necessary that there be openings in the resonator walls so that an electron beam may pass through the cavity resonator. These openings should be as large as possible without destroying the cavity resonator itself, since it is only those electrons that interact with the alternating field contained in the cavity resonator which deliver power thereto or extract power therefrom.

It is an object of this invention to provide a novel and improved construction and method of manufacture of cavity resonators incorporating the above advantages.

It is a further object of this invention to provide a construction and method of manufacture of cavity resonators in which the component parts may be manufactured as units and the final resonator assembled at a later time.

Another object of this invention is to provide

2

a convenient construction and method of manufacturing cavity resonators having large mass and efficient heat conducting properties so as to maintain all parts of the resonator at as nearly an equal temperature as possible.

Still another object of this invention is to provide a novel and convenient construction and method of manufacturing cavity resonators which are to be used in electron discharge tubes or similar devices, in which the power output is to vary from tube to tube, while the resonant frequency of each tube is to remain the same.

A further object of this invention is to provide an improved construction and method of manufacturing cavity resonators in which electron beams of large cross section can be projected into the alternating electromagnetic field of a cavity resonator.

In accordance with the present invention, there is provided a novel and improved method of constructing and construction for cavity resonators. This improved method consists of the manufacture of laminations which have a volume removed from them which is similar to the desired cross section of the cavity resonator; for example, toroidal shape. The laminations are preferably thin for ease in manufacture, but in many applications they may be of substantial thickness. The surface of these laminations in most applications is formed of copper or a similar metal of high electrical conductivity. This can be accomplished by electroplating or evaporating metals of high conductivity on the formed laminations, or manufacturing the laminations themselves from such materials. The laminations are stacked together so that the volumes which are removed from them form a cavity with conducting walls. Semicircular end sections which may have openings in the shape of semi-toroids are placed at each end of the stack of

40 laminations to complete the cavity resonator structure. The inner surface of these end sections is also copper or a similar metal. By a suitable heat treatment the laminations and the end sections are consolidated so as to make one unitary cavity resonator structure. Special arrangements provide for the passage of electrons through the resonator.

The invention in another of its aspects relates to novel features of the instrumentalities described herein for achieving the principal objects of the invention and to novel principles employed in those instrumentalities whether or not these features and principles are used for the said principal objects or in the said field.

A further object of the invention is to provide improved apparatus and instrumentalities embodying novel features and principles, adapted for use in realizing the above objects and also are adapted for use in other fields.

Other objects of the invention will be more apparent from the following description taken in connection with the accompanying drawings in which a preferred form of the invention is shown.

In the drawings,

Fig. 1 is a longitudinal cross-sectional view of an electron discharge device incorporating an embodiment of this invention;

Fig. 1A is a cross-sectional view of the embodiment shown in Fig. 1 taken along line A:A thereof;

Fig. 1B is a similar cross-sectional view taken along line B:B in Figs. 1 and 1A;

Fig. 2 is an oblique exploded view of the cavity resonator shown in Fig. 1;

Fig. 3 is a cross-sectional view of part of a cavity resonator structure including its tuning mechanism; and

Fig. 4 is an oblique exploded view of a resonator structure incorporating a pair of cavity resonators.

Fig. 1 shows a longitudinal cross-sectional view of a reflex type of klystron, the operation of which is described with respect to Fig. 2 of U. S. Patent No. 2,250,511. In this embodiment of the invention a substantially rectangular flat cathode 10 is heated by a long heater coil 11, heating current being supplied through supporting heating leads 12, which terminate in lead-in caps 13 in cathode shell 21. Cathode 10 is supported by leads 14 which terminate in lead-in caps 15.

The electrons which are emitted by cathode 10 pass up through the openings in the walls of cavity resonator 16 and are reflected back by a substantially flat reflector electrode 17. This reflector electrode 17 is supported by rods 18, which also serve as leads to supply the reflector electrode 17 with suitable potential. The rods 18 terminate in reflector electrode lead-in caps 19. The complete structure is enclosed in an evacuated chamber formed by reflector shell 20 and cathode shell 21 which are vacuously sealed to the cavity resonator 16. The heater leads 12 and cathode leads 14 are insulated electrically from the cathode shell 21 by glass seals 22. In a similar manner, reflector electrode leads 18 are insulated electrically from the reflector shell 20 by glass seals 23.

The cavity resonator 16 in the above embodiment is shown in greater detail in Fig. 2. In this type of structure, preferably thin laminations 24 (say from .05 to .10 inch) are used. These laminations 24 have volumes 25 and 26 removed from them, in the shape of a narrow central opening 26 and circular end openings 25, the complete openings 25, 26 being similar to the "dumbbell" cross-section in the conventional toroidal-shaped cavity resonator such as shown in U. S. Patent No. 2,242,275. It should be understood that the complete opening 25, 26 could be of many other shapes, as desired for the resonator, since the resonator could be of any shape according to the characteristics desired for the device employing the resonator. Since the laminations 24 are preferably thin, a convenient method of manufacturing would be by punching or stamping out these volumes 25 and 26. However, the invention is not concerned with the manner in which the laminations are fabricated. The volumes 25 and 26 may be removed by milling or machining or the laminations 24 themselves

might be cast with the volumes 25 and 26 already provided.

These thin laminations 24 are preferably made of copper or a similar metal. However, it is quite possible that they may be made of different metal than copper, but in such a case their surface is preferably of copper or a similar conductive metal. Thus, for example, they may be constructed of steel or Invar and plated with copper or silver, or they may be cast of iron and sputtered with a good conductor.

In assembly, these thin laminations 24 are separated from one another by pairs of spacers 27 and 28. When viewed in cross section, it is seen that these spacers 27 and 28 also have volumes 29 and 30 removed from them. These volumes 29 and 30 correspond to only the circular portions 25 of the opening in the thin laminations 24. There is no spacer between the laminations 24 adjacent to the central volume 26 of laminations 24 which connects the circular volumes 25.

The spacers 27 and 28 are preferably made in a fashion similar to laminations 24. As in the case of the laminations 24, the essential feature in most applications is that the surface consists of a good conductor. An exemplary method that suggests itself for the construction of these spacers 27 and 28 is the longitudinal drilling of a bar of copper. After the bar has a hole drilled through it, whose diameter is that of the cylindrical opening 25 of the cavity resonator desired, it is cut into sections of suitable sizes for storing and later as an assembly. Another method that lends itself quite neatly to the mass production of such pieces would be die casting. This would assure uniformity of pieces at a minimum of cost.

The thin laminations 24 and pairs of spacers 27 and 28 are stacked alternately until a resonator 16 of desired length is obtained. In order to complete the cavity resonator 16 and make a completely enclosed volume, semicircular end sections 55 are provided at each end. The semicircular end sections 55 have a semitoroidal volume 56 removed from them, the openings of which line-up with the circular opening 25 of the thin laminations 24 and with the openings 30 of the spacers 27 and 28. These semicircular end sections 55 could be manufactured in any of several ways. One such way is by providing two portions each having half the desired thickness of the complete end section. Half the semitoroidal volume 56 could be removed from each such portion. Thereafter, the two portions could be joined. This would result in a semicircular end section of the desired thickness with the semitoroidal volume 56 removed. The two halves could be preliminarily consolidated to form a unitary end section 55 or they could be merely clamped together and consolidated in a later operation.

After stacking laminations 24, spacers 27 and 28, and end sections 55 together, they are given a suitable heat treatment (i. e., soldering, brazing, etc.), so that the component parts consolidate to form a unitary structure. The resonator 16 thus formed can then be used in an electron discharge tube such as shown in the embodiment in Fig. 1.

As is seen in Fig. 1A, because of the present novel structure, it is possible to have a large unobstructed area 31 across which electrons may flow formed by the separation between the pairs of spacers 27 and 28. Since this construction permits only a minimum number of electrons which are emitted by the cathode 10 to be intercepted as they pass thru the alternating electro-

magnetic field of the cavity resonator it allows the usable power of the electron discharge tube to be increased.

The cavity resonator 16 thus formed has many of the features which are considered desirable in resonator construction. It has been constructed of components which are themselves quite easy to manufacture. The resulting resonator assembled from these premanufactured parts has a considerable mass surrounding the cavity resonator, such mass having high heat conductivity which aids in maintaining all parts of the cavity resonator at substantially equal temperatures.

As has been discussed, an electron beam of large cross-section can be projected into the alternating electromagnetic field of the cavity resonator. Since a minimum number of electrons in the beam are intercepted the usable power of the electron tubes using this construction is large. Furthermore, tubes of different amounts of power but with the same frequency could be assembled as desired merely by stacking a sufficient number of laminations and spacers together until the correct cavity resonator dimensions are obtained, since the resonator frequency is determined by the shape of the opening 25, 26 and not by the overall resonator length. Such a cavity resonator, used with a cathode and reflector plate of comparable dimensions, would thus result, when assembled, in a reflex klystron of a power output predetermined by the number of laminations used, and of correct frequency. Thus, by having stock cathodes and reflector plates of different sizes and laminations, spacers, and end sections as described, reflex klystrons could be assembled quickly and conveniently having predetermined power outputs covering a large range, all such klystrons having the same desired frequency. For different frequencies, different laminations, spacers and end sections are used, but with the same cathodes and reflectors.

If it is desired to construct a cavity resonator which is not to be used in electron discharge devices, the spacers 27 and 28 can be omitted. In this way, by stacking a sufficient number of identical laminations 24 and using two end sections 55, it is possible to quickly and conveniently assemble a cavity resonator from premanufactured units.

In order to remove electromagnetic energy from the cavity resonator, coupling loops are used. Such a coupling loop is constructed in one of the spacers 32, shown in Fig. 2. The cross-section of such a spacer 32 is shown in Fig. 1A and in Fig. 1B. A small loop 33, which links the magnetic field in the cavity resonator 16, is constructed within the spacer 32. This loop 33 terminates in a coaxial line 34 sealed into the rear of spacer 32. Since the resonator is part of a vacuum system, the coaxial line 34 includes a glass-to-metal seal 35.

Tuning cavity resonators made in accordance with this invention may be accomplished in a variety of ways. One form of tuning apparatus is shown in Fig. 1A. A metal rod 36 which extends the length of resonator 16 is supported in a recess 37 which is in addition to the removed volumes 25, 26 and 30 of both the laminations 24 and spacers 28. This may be better understood by reference to Fig. 1B, which is a cross-sectional view taken along the line B—B of Fig. 1A. This rod 36 is shaped so that a portion of it forms a continuation of the inner circular portion of the

cross-section of the cavity resonator 16. As the rod 36 is rotated about its axis 38 by knob 39, shown in Fig. 1A, the cross-section of the resonator 16 is changed. The resulting field disturbances cause a change in resonant frequency. Knob 39 is sealed to a cylinder 60 which in turn is sealed to the resonator cavity, to maintain the vacuum envelope. If the tuning mechanism is to be used merely as a trimmer in adjusting the resonant frequency of the cavity resonator 16 over small amounts, and quite infrequently, the walls of the cylinder 60 may be made of a ductile metal. However, if the tuning mechanism is to be used repeatedly and over large ranges, it is preferable that the walls of the cylinder 60 be of a resilient metal. In such a case, it is necessary to provide some sort of a locking fixture to the tuning mechanism, such as a lock nut 61 which moves on threads 62 provided on the outside walls of cylinder 60. This lock nut 61 shoulders against the face 63 of the end section 65, and maintains the rod 36 in the proper angular position after it is turned by knob 39.

Another method of tuning that may be used in a resonator constructed according to this invention is shown in Fig. 3, which is a cross-section of one of the spacers 28. In this method of tuning, a metal bar 40 which extends the length of the resonator 16 is supported in a recess 41 which is in addition to the removed volume 30 of the spacer 28 and the removed volume 25 of the thin lamination 24. The inside face 42 of the metal bar 40 ordinarily forms a smooth continuation of the resonator wall. By the use of a rod or rods 43 which pass through a vacuum seal 44 of the bellows type, the metal bar 40 may be moved sideways into the resonator 16, distorting the field therein and causing a change in the resonant frequency.

Although the embodiment of the present invention described above uses but a single cavity resonator, it is quite possible to construct multiple resonators in the same manner. Fig. 4 shows an oblique exploded view of parts for a two-resonator structure. The thin laminations 45 have two volumes 46 and 47 removed from them. These volumes 46 and 47 are similar to volumes 26 and 25 of the thin lamination 24 shown in Fig. 2. Pairs of spacers 48 and 49 have removed volumes 50 and 51 which are similar to the removed volumes 29 and 30 in spacers 27 and 28 also shown in Fig. 2. The semicircular end section 52 has two semitoroids 53 and 54 removed from it in the manner of semitoroid 56 of end section 55 in Fig. 2. The volumes 46 and 47 of the laminations 45 and the corresponding portions 50 and 51 of the spacers 48 and 49, and the portions 53 and 54 of the end section 52, are spaced from one another in such a manner so as to provide a drift space of the proper dimensions to allow for proper bunching of the electrons as they pass up through the space between spacers 48 and 49. If internal coupling between the two resonators is desired, one or more of the laminations 45 may have a further opening 70 joining the circular openings 47, 46.

Thus, the manner of manufacture and assembly of a double resonator is the same as that of a single resonator. The component parts, whose surfaces in most applications are good conductors, are consolidated by proper heat treatment and the resulting structure is a double cavity resonator formed of premanufactured parts. Methods of tuning and coupling of electromagnetic energy used in the single cavity resonator may

easily be applied to such a double cavity resonator.

Thus it can be seen that in accordance with this invention, a cavity resonator may be constructed using premanufactured elements and having any desired length, corresponding to a predetermined power capacity. The mass surrounding the cavity resonator would be of sufficiently high conductivity to allow the heat which is generated in the resonator to be quickly conducted to the exterior, keeping all parts of the resonator at substantially equal temperatures. Thus temperature compensation can easily be accomplished with the resultant increase in frequency stability. Furthermore, cavity resonators constructed according to this invention provide means whereby beams of electrons of large cross-section can be projected into the alternating electromagnetic field of the cavity resonator with a minimum number of such electrons being intercepted by the cavity resonator itself, thereby increasing the usable power.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. A unitary cavity resonator for supporting electromagnetic oscillations formed of a plurality of thin conductive-surface laminations having a relatively long dimension, a plurality of relatively thick conductive-surface spacers each being less than one-half as long as said long dimension of said laminations, and a pair of conductive-surface end sections, each of said laminations and end sections having corresponding openings therein, each of said spacers having an opening therein which corresponds to at least part of the opening in said laminations and end sections, pairs of said spacers being disposed between successively spaced laminations, each pair of said spacers comprising one spacer between adjacent ends of two laminations and the other spacer between the other ends of said two laminations, said openings in said spacers being in register with the corresponding part of said openings in said laminations and forming continuous passages therewith, said successively spaced laminations and said pair of spacers therebetween defining gaps surrounded at least substantially by said passages; said laminations and spacers and end sections being consolidated to form a unitary structure in which said openings and said passages define a smooth-walled unitary cavity with conductive walls, said unitary cavity being resonant at a predetermined frequency for electromagnetic oscillations.

2. A unitary cavity resonator structure adapted to contain ultra high frequency electromagnetic oscillations, said structure being formed of a plurality of conductive-surface laminations, a plurality of conductive-surface spacers and a pair of conductive-surface end sections, each of said laminations and end sections having corresponding openings therein, each of said spacers having an opening therein which corresponds to at least part of the said openings of said laminations and end sections, said laminations, spacers and end sections being consolidated to form a unitary structure in which said openings define a unitary cavity with conductive walls, said laminations

consolidated in said unitary structure defining a plurality of regularly spaced passages parallel to said laminations and transverse the unitary cavity for the passage of an electron stream transverse the cavity, said unitary cavity being resonant at a predetermined frequency.

3. A unitary multiple resonator structure adapted to contain ultra high frequency electromagnetic oscillations, said structure being formed of a plurality of conductive-surface laminations, a plurality of conductive-surface spacers and a pair of conductive-surface end sections, each of said laminations having a plurality of separate openings therein, each of said end sections having a similar plurality of separate openings therein which correspond to said first separate openings, each of said spacers having a plurality of separate openings therein which correspond to at least part of said openings, of said laminations and end sections, said laminations, spacers and end sections being consolidated to form a unitary structure in which said openings define a plurality of cavities of a fixed and predetermined separation, open spaces being provided at regular intervals between successive spaced portions of said laminations in said structure whereby multiple parallel passages extend transverse said cavities through which an electron stream may pass to provide tandem interactions with said cavities, each of said cavities being resonant at a predetermined frequency.

4. A unitary cavity resonator structure adapted to contain ultra high frequency electromagnetic oscillations, said structure being formed of a plurality of conductive-surface laminations, a plurality of conductive-surface spacers and a pair of conductive-surface end sections, each of said laminations and end sections having corresponding openings therein, each of said spacers having an opening therein corresponding to at least part of said laminations and end sections, one or more of said spacers having a coaxial line sealed to it, one end of said coaxial line terminating in a coupling loop located inside of removed portions of said spacers, said laminations, spacers and end sections being consolidated to form a unitary structure in which said removed portions define a unitary cavity with conducting walls and resonant at a predetermined frequency, said unitary structure including plural parallel passages therethrough along lines surrounded by said conducting walls of said unitary cavity, each passage being bounded on two sides by parallel surfaces of successive laminations and being bounded at its two ends by the inner ends of a pair of spacers between the successive laminations defining the passage.

5. A unitary cavity resonator structure adapted to contain ultra high frequency electromagnetic oscillations, said structure being formed of a plurality of conductive-surface laminations and a pair of conductive-surface end sections, each of said laminations and end sections having corresponding openings therein, said laminations and end sections being consolidated to form a unitary cavity with conducting walls and resonant at a predetermined frequency, a tuning rod of noncircular cross-section extending through said openings and perpendicular to said laminations, and means for imparting rotational displacements to said rod about its longitudinal axis, whereby said resonant frequency is correspondingly changed.

6. A unitary cavity resonator structure adapted to contain ultra high frequency electromagnetic

oscillations, said structure being formed of a plurality of conductive-surface laminations, a plurality of conductive-surface spacers, and a pair of conductive-surface end sections, each of said laminations, spacers and end sections having corresponding openings therein, said laminations, spacers and end sections being consolidated to form a unitary structure in which said openings define a unitary cavity with conductive walls and resonant at a predetermined frequency, said unitary cavity having at least one straight portion of appreciable length extending transversely through a multiplicity of said laminations, a tuning rod extending an appreciable distance along said straight portion of said cavity, the longitudinal axis of said rod being parallel to said straight cavity portion and perpendicular to said laminations, and means for varying the disposition of said rod with respect to the interior of said cavity to correspondingly change said resonant frequency.

7. Cavity resonator structure for supporting electromagnetic oscillations therein, including conductive means having an endless tubular cavity, said tubular cavity comprising two oppositely disposed and parallel tubular passages, and two curved tubular end section passages, the innermost circumferential surface portion of said endless tubular cavity being open to define an endless narrow gap therealong, and a plurality of spaced cross-members extending transversely between said parallel passages and each having a slot extending therealong interconnecting said parallel passages at the narrow gap thereof, whereby the spaces between successive cross-members define electron permeable electrode

structure surrounded by said endless tubular cavity.

8. Electron discharge tube apparatus, comprising conductive means having an endless tubular cavity, said tubular cavity comprising two oppositely disposed and parallel tubular passages, and two curved tubular end section passages, the innermost circumferential surface portion of said endless tubular cavity being open to define an endless narrow gap therealong, and a plurality of spaced cross-members extending transversely between said parallel passages and each having a slot extending therealong interconnecting said parallel passages at the narrow gap thereof, whereby the spaces between successive cross-members define electron permeable electrode structure surrounded by said endless tubular cavity, and cathode means for emitting an electron stream through the spaces between said successively spaced cross-members and having an elongated electron emitting surface extending parallel to said parallel passages.
